DESIGN FOR A WASHING MACHINE

David Chapman, Chicago, Ill., assignor to The Apex Electrical Manufacturing Co., Cleveland,
Ohio, a corporation of Ohio

Application March 24, 1945, Serial No. 118,663

Term of patent 14 years

(Cl. D49—1)

To all whom it may concern:

Be it known that I, David Chapman, a citizen of the United States of America, residing at Chicago, in the county of Cook and State of Illinois, have invented a new, original, and ornamental Design for a Washing Machine, of which the following is a specification, reference being had to the accompanying drawings, forming a part thereof.

In the drawings:

The side of the washing machine not shown in Fig. 2 is substantially the same as the side shown. The dominant features of the design reside in the portions shown in full lines.

I claim:

The new ornamental design for a washing machine, substantially as shown and described.

DAVID CHAPMAN.
